UNITED STATES PATENT OFFICE.

WILHELM ULRICH, OF ESSEN-ON-THE-RUHR, GERMANY, ASSIGNOR TO
FRIED. KRUPP AKTIENGESELLSCHAFT, OF ESSEN-ON-THE-RUHR,
GERMANY.

CARTRIDGE.

SPECIFICATION forming part of Letters Patent No. 777,319, dated December 13, 1904.

Application filed May 2, 1904. Serial No. 206,047. (No model.)

To all whom it may concern:

Be it known that I, WILHELM ULRICH, a subject of the Emperor of Germany, and a resident of Essen-on-the-Ruhr, Germany, have invented certain new and useful Improvements in Cartridges, of which the following is a specification.

The present invention relates to those cartridges or cartouches in which a so-called "auxiliary" or "priming" charge is arranged between the percussion-cap and the main driving charge, which has the effect of reinforcing the fire coming from the percussion-cap, and thereby insuring a safer ignition of the driving charge. In cartridges or cartouches of this type the auxiliary or priming charge has usually been arranged in a bag and this bag placed between the driving charge and the base of the shell in immediate contact with the latter. In such arrangements there is great danger of the auxiliary-charge bag becoming penetrated in transportation of the cartridge or cartouche in consequence of the pressure of the driving charge resting upon it, as well as the pressure of its own mass, followed by the scattering and dissipating of the auxiliary charge and its failure to perform its function.

The present invention has for its object to avoid this possibility, and this object is attained by securing the auxiliary charge to the dome of a hollow chamber which is provided between the base of the cartridge and the driving charge, the arrangement as well as the dimensions of the hollow chamber and auxiliary charge being so selected that notwithstanding any vibrations of the parts the auxiliary charge cannot come in contact with the percussion-cap chamber or with the base of the shell.

In the accompanying drawings, forming part of this specification, three embodiments of the invention, by way of example, are illustrated by portions of three cartridges shown in vertical longitudinal section.

Referring first to the embodiment illustrated in Figure 1, a bell-shaped part C rests upon the base B of the cartridge-shell, which bell-shaped part may be constructed of brass, pasteboard, press-board, smokeless powder,

or the like. The dome c' of this part supports the driving charge D, which may be, for example, tubular powder. Within the part C is a bag F, containing the auxiliary charge E, secured to the dome c' in any desired manner—for example, by pasting, sewing, &c. The interior height of the part C and the thickness of the bag containing the auxiliary charge are so determined that ample room is provided between the bag F and the shell-base B or percussion-cap chamber b' to avoid contact of the bag with such parts notwithstanding any vibration which occurs with the dome c'. To facilitate passage of the fire from the auxiliary charge to the driving charge, the dome c' is suitably provided with bores c². From the drawings it will be clearly understood that the described arrangement will absolutely prevent the penetration of the auxiliary bag and the scattering and dissipating of the auxiliary charge in a safe manner.

According to the embodiment of the invention illustrated in Fig. 2 the auxiliary charge E is carried by an inserted part C, as in Fig. 1; but a bowl-shaped depression c³ in the dome of the inserted part serves as a container for the auxiliary charge E, so that a special bag for this charge is not necessary. The container c³ is closed in the direction of the driving charge D by a cover c⁴, pasted or otherwise secured in position. In the bottom of the depression c³, as also in the cover c⁴, bores may be provided for the passage of the fire, and these bores may be closed against the escape of the auxiliary charge by pieces of gauze or the like.

According to the embodiment shown in Fig. 3 the walls of the bell-shaped hollow chamber are formed by the driving charge D itself. For this purpose the inner tubes d' of a suitably-bound bundle are made shorter to a certain extent than the outer tubes d² at the end of the bundle presented toward the base of the cartridge-shell, and this relative position of the tubes is secured by suitable means—for example, strongly tying the bundle. The bag F, containing the auxiliary charge E, is then attached immediately to the inner tubes d'. It is obvious that without departing

from the scope of this invention the auxiliary charge could be supported from a false bottom which is sustained on projections extending a suitable distance within the shell to hold the auxiliary charge away from the percussion-cap chamber, it being obvious that in such a case the side walls of the bell-shaped hollow chamber would be present in the walls of the cartridge-chamber itself and the dome of the chamber constituted by the false bottom.

Having described the invention, the following is what is claimed as new therein:

1. A cartridge or cartouche having a hollow chamber provided between the driving charge and the percussion-cap, and an auxiliary or priming charge supported within the chamber from the dome thereof to prevent the said auxiliary charge from contacting with parts that tend to injure it in transportation of the cartridge or cartouche.

2. A cartridge or cartouche, provided with an inserted part forming a hollow chamber between the driving charge and the base of the shell, and having an auxiliary or priming

charge supported from said inserted part in position to avoid contact with other parts of the shell that would tend to injure it.

3. A cartridge or cartouche, provided with a bell-shaped inserted part providing a chamber between the driving charge and the percussion-cap and having an auxiliary or priming charge supported by said inserted part and held thereby out of contact with other parts which would tend to injure the auxiliary charge.

4. A cartridge or cartouche, provided with a bell-shaped part inserted between the driving charge and the percussion-cap; said inserted part being formed with a depression and having an auxiliary charge located in said depression for the purpose set forth.

The foregoing specification signed at Düsseldorf this 21st day of April, 1904.

WILHELM ULRICH.
